Inventor.

Walter William Nobbs.

UNITED STATES PATENT OFFICE.

WALTER WILLIAM NOBBS, OF LONDON, ENGLAND.

VENTILATOR.

1,310,429.

Specification of Letters Patent.

Patented July 22, 1919.

Application filed October 1, 1915. Serial No. 53,593.

To all whom it may concern:

Be it known that I, WALTER WILLIAM NOBBS, a subject of the King of Great Britain, residing at 71 Haverstock Hill, 5 London, England, have invented certain new and useful Improvements in Ventilators, of which the following is a full, clear, and exact description, reference being had to the accompanying drawing, which forms 10 a part of this specification.

My invention relates to a ventilator of the type in which is provided an air conduit, having the usual regulating grating at one end and an air filter located in the 15 conduit behind or below the grating depending upon whether the conduit is vertically or horizontally arranged. It is an object of my invention to provide an air filter of large surface compared with the 20 cross sectional area of the conduit, and which may be readily inserted and removed from the conduit without removing the grating or a radiator or other object which may be disposed in front of or above said grating. 25 It is also an object of my invention to so shape the filter and so arrange it relative to the conduit, that foreign matter filtered from the air passing through the conduit, will be stopped and deflected by the filter 30 to a position from which it may be readily removed.

These objects I obtain by the construction described in the annexed specification and illustrated in the accompanying drawings in which—

Figure 1 is a vertical section through one form of the ventilator substantially on the line I—I of Fig. 2, the relative position of the usual radiator being shown in dotted 40 lines;

Fig. 2 is a front elevation of the ventilator;

Fig. 3 is a section of the ventilator on the line I—I of Fig. 2 with the grating 45 and filter removed;

Fig. 4 is a horizontal section on the line IV—IV of Fig. 3 and

Figs. 5 and 6 are views similar to Fig. 1, showing modified forms of filters.

Similar reference characters refer to similar parts throughout the views.

Referring now to the drawings; “b” represents a conduit or air passage, which in the embodiment of the invention is an opening through the wall of a building for the purpose of conducting fresh and cold air

from the exterior of the building to the interior thereof. At the inner end of the conduit is located a ventilator frame forming in part an end closure “a” preferably set in 60 flush with the interior wall of the building. As shown in the drawing this frame is rectangular, and serves as a support for the grating “d” provided with the usual regulating shutters “w.” The vertical dimension 65 of the grating “d” is less than that of the frame “a” thus providing a narrow rectangular opening through which access may be had to the conduit “b.” In the form of the invention shown in Figs. 1 to 4 this 70 opening is provided with a door “h” hinged at the bottom to suitable projections on the frame “a” and held in closed position by the latch “l.”

The position of the usual radiator relative 75 to the ventilator is indicated in Fig. 1 in dotted lines. As shown a radiator “f” of the well known type rests on a saddle “o” suspended from the bracket “g” by bolts “p.” A hook connection indicated at “v” 80 may be used to further secure the radiator in place. As will more clearly appear hereinafter it is not necessary to disturb the radiator either to clean the conduit or to insert the air filter, so that the radiator may 85 be permanently secured in position.

As shown more clearly in Figs. 3 and 4, the vertical walls of the frame “a” are provided with curved grooves or guides “i” 90 preferably increasing in width at the lower ends thereof. These grooves form the support for a curved air filter “e”. The filter may be composed of the usual air filtering material preferably a wire screen of fine mesh.

By making the filter curved, a large filtering surface is provided and the filter may be readily inserted and removed. For example, in the embodiment of the invention shown in Figs. 1 to 4, the filter “e” may be inserted 100 beneath the radiator and grating through the door “h”, the filter being shown in dotted lines in the position it occupies just before insertion and in full lines in the position it occupies after insertion in the conduit 105 “b”. The grooves “i” serve as guides while the filter is being inserted, the wide lower end of such grooves facilitating such insertion. It is apparent that the filter “e” may be readily inserted and removed 110 without disturbing either the grating “d” or radiator “f”. Obviously also the filter may

be formed of flexible material and the guide grooves "i" relied upon to give the surface of the filter a curved form after it has been inserted.

5 In the modification of the invention shown in Fig. 5 the grooves "i" in the frame "b" are given a slightly different form from those shown in Fig. 1; these grooves starting from the upper and outer corners of the 10 side walls, gradually curving to the inner lower corners. While the curvature of the filter in this case is not as great as in Fig. 1, the filter serves to deflect foreign matter filtered from the air in the conduit to a point 15 adjacent the door "h" through which it may be readily removed.

In the modified form of the invention shown in Fig. 6 the filter "e" is hinged to the door "h" which in this case is not attached to the frame "a". The upper edge 20 of the filter is provided with apertures which engage hooks or studs "x" when the filter is inserted. In this modification when the door "h" is removed the filter is removed 25 with it.

Obviously the amount of curvature of the filter "e" when once inserted may vary within wide limits without departing from the spirit of the invention as it is conceivable 30 that even a substantially flat surfaced filter could be employed if of sufficient flexibility to permit its insertion behind the grating without removing the grating. Also the conduit may be vertically arranged in which 35 case the filter would also serve to prevent foreign matter from entering the conduit from above.

I claim:

1. A ventilator comprising an air conduit 40 having continuous side walls and an end

closure, an air filter, means for holding said air filter in substantially transverse position in said conduit, a grating centrally carried by said end closure, and an opening in said end closure separate from and situated on 45 one side of said grating and so related to said holding means that said air filter may be removed and replaced therethrough without disturbing said grating.

2. A ventilator comprising an air conduit 50 having continuous side walls and an end closure, an air filter, grooves or guides carried by said side walls for holding said air filter in position substantially transverse to said conduit, one end of said grooves or 55 guides being adjacent said end closure and a narrow opening in said end closure adjacent the ends of said grooves or guides through which said air filter may be removed and replaced.

3. A ventilator comprising an air conduit having continuous side walls and an end closure, a curved air filter, curved grooves or guides carried by said side walls for holding said air filter in position substantially transverse to said conduit, the lower portion of said air filter as held by said grooves or guides being nearer said end closure than the central position thereof and a door provided for an opening in said end 70 closure at the bottom thereof, such opening being adjacent the ends of said grooves or guides and the lower portion of said air filter whereby said air filter may be removed and replaced.

WALTER WILLIAM NOBBS.
